Application August 22, 1938, Serial No. 226,153

5 Claims.

(Cl. 2—73)

This invention relates to new and useful improvements in garments for ladies, and relates more specifically to an improved undergarment or slip.

5 One of the principal objects of the present invention is the provision of an improved ladies' body garment consisting of a waist and a skirt portion which is formed substantially upon the straight of the material and wherein a bias effect is created in the waist and bust-encircling portions by means of throwing the grain of the material in such portions at a distinct angle to the straight of the material by the formation of a particular type of dart.

10 15 Ladies' slips or other similar garments have, for the most part, been formed upon the bias of the material in order to give the garment an approved measure of circumferential elasticity or stretchability in order to accommodate the normal increased girth of the wearer when she is in a sitting position. Bias cut slips, however, have been objectionable for the reason that when the garment does so expand when the wearer is sitting, the increased girth must be compensated for 20 by the garment being shorter, thereby causing the dress of the wearer to ride upwardly along with the undergarment.

25 Straight cut garments of the usual type have, to a large extent, been objectionable because no suitable measure of elasticity is provided when the wearer is sitting, and it is accordingly one of the objects of the present invention to provide an improved garment constructed substantially on the straight of the material which will accommodate itself to the body of the wearer while sitting and still not decrease in length at such time.

30 35 A further object of the invention is the provision of a garment having a bias-cut seam in the rear of the garment, provision for such bias seam being made by rearranging the grain line of the material in such portions.

40 Another object of the invention is the provision of an improved garment, the main body portion of which is constructed from a single blank of material, the front median line of the garment being on the straight of the goods, and wherein a distinct saving of material is effected through the novel details of construction. Yet another 45 object of the invention is the provision of an improved garment which may be made in the form of either a slip, nightgown, or dress, wherein only a single vertical seam is provided, this seam being at the rear of the garment, and wherein the fitting qualities of such garment are greatly im-

proved over conventional articles of this general character.

In the drawings:

Fig. 1 is a front elevation of the garment on the body of the wearer;

Fig. 2 is a rear elevation thereof;

Fig. 3 is a plan view of the blank employed in making the main body portion of the garment;

Fig. 4 is a plan view of the two blanks used in constructing the rear lower portion of the garment, which portion, however, may be made from a single blank;

Fig. 5 is a plan view of the finished garment folded along its front and rear vertical center lines;

Fig. 6 is a plan view of the folded blanks, the view showing the method of dart formation in the main blank in order to produce the bias effect in the waist portion of the garment;

Fig. 7 is a rear elevation of a modified garment 20 wherein a rear panel extends the full length of the garment.

A ladies' undergarment or slip is chosen for illustration of the preferred embodiment of the invention in the drawings, although it will be appreciated that substantially the same structure may be employed for other body garments, including nightgowns, dresses, or the like.

The main body portion of the garment is made from a substantially square piece of material or blank 10, the grain 11 of such material being parallel with the respective edges of the blank. In constructing the garment, the blank is first folded along the central vertical line, shown at x—x in Fig. 3, such line constituting the front median line of the garment, as indicated at 13 in Figs. 5 and 6. A dart is now formed in each side of the upper waist portion of the garment, which dart is formed by cutting each side of the blank in substantially the manner shown in Fig. 6. The upper horizontal edge 14 of the cut-out portion is somewhat curved throughout its length and the lower edge 15 of such cut-out portion is formed with a slightly greater curve than the edge 14. The upper edge 20 of this laterally extending portion is concavely curved in the manner shown. A short, substantially vertical edge 16 is provided at the inner end of the curved edge 15, and another substantially vertical edge 17 at an acute angle to the edge 16 joins the edge 16 with the inner terminal of the upper horizontal edge 14.

Each half of the garment is cut in this fashion and the edges 16 and 17 are now joined together along the stitch lines 18 and 19, respectively, which lines are spaced from the marginal edges 23

an approved amount. The upper and lower curved edges are then joined together along the stitch lines 21 and 22, respectively. Thus two darts are formed on each side of the garment, one, an elongated, substantially horizontal dart 30 terminating at the bust portion, and a short dart 31 extending upwardly from such point of termination, over the bust portion. This latter dart is made on the bias relative to the front median line 13 of the garment, as shown in Fig. 5, in order to give such bust portions a greater measure of flexibility. It should be noted that the point 23 which forms the junction of the stitch lines 18 and 22 should coincide with the point 24 which forms the junction of the stitch lines 19 and 21. Thus, when the upper and lower edges 14 and 15 are secured together along the stitch lines 21 and 22, the grain of the material in the waist portion of the garment above the edge 14, indicated as 26, is thrown on the bias with respect to the material below the edge 15.

In the drawings the stitch line 21 is shown as being of substantially the same length as the stitch line 22, although if a greater measure of fullness in the upper bust-encircling portions of the garment is required, this stitch line 21 may be somewhat longer than the lower stitch line 22. Conversely, in the event that a lesser measure of fullness is required, the stitch line 22 may be longer than the stitch line 21.

The precise formation, curvature and length of each horizontal edge 14 and 15, and of each substantially vertical edge 16 and 17 is dependent upon the shape and size of the figure of the wearer to be fitted by the garment. In a fair range of sizes, these edges will vary considerably and in some instances one or both of the edges 14 and 15 may be partially straight throughout a good portion of their lengths. In the preferred embodiment of the invention, however, these edges are curved throughout their lengths and constitute segments of different circles. It may be further pointed out that in the event it is necessary to make the edges 14 and 15 of unequal lengths, in order to produce a certain effect, the longer edge is progressively fulled into the shorter edge as the edges are stitched together.

The foregoing dart construction differs from darts and tucks generally in that its primary purpose is to swing or rotate the grain of the material from a straight grain in the front central portion of the garment to a bias in the rear portion of the garment, particularly at the upper end thereof. When the darts are formed substantially in the manner described, the requisite varying of the grain of the material is accomplished and the desired fullness follows almost as a natural result. Darts and tucks generally are for the purpose of creating or reducing fullness and no desired throwing of the grain line results.

To further clarify the method of creating these darts for any given size or figure, in order to make it more understandable to those skilled in the art, it may be stated that a horizontal cut is made generally along the line 15 (Fig. 6). The material is placed upon the form with the front median line properly positioned and the material below the line 15 is then positioned to give the desired bias relative to the front median line, the grain lines just below the reference character 30 in Fig. 5 showing generally the approved degree of bias. The upper portion 26 extending laterally from the bust portion is now brought downwardly or rotated to give the desired bias therein, which bias is desirably of somewhat greater degree than

the bias below line 15. This rotation of the portion 26 brings the lower edge 14 thereof inwardly toward the front of the garment and when this portion is properly positioned relative to the portion below the edge 15, the stitch lines 21 and 22 are readily determined. There is now a surplus of material over the bust portion and the stitch lines 18 and 19 of the short dart then determined, keeping in mind, of course, that a bias dart is desired here. It must be appreciated, however, that this short dart extending upwardly over the bust portion probably is, and may in fact be considered as, an upward extension of the long dart. The surplus material may now be trimmed away.

If the general angle of the short dart is known at the time the first cut (15) is made, a short upwardly extending cut may also be made here at this time, which cut aids in determining the stitch line of this short dart, the angle of which, relative to the long dart, is of great importance. Also, it must be made clear that this entire process may be reversed and the angle and contour of the short dart determined first, the stitch line made, and the long dart formed last.

In actual construction of the garment, each side of the blank may be first stitched along the stitch lines 18 and 19 and then along the stitch lines 21 and 22, and the material cut therefrom thereafter. For the sake of clearness in Fig. 6, however, the blank is indicated as being cut in the first instance and stitched thereafter. In view of the fact that the stitch line 21 prior to the stitching operation occupies a position to the left of the stitch line 22, this portion must be moved over to coincide with such lower stitch line 22, and for the sake of clearness, the upper and lower edges 14 and 15 are shown with the small cut-out portions 28, and a broken line 29 extends between such cut-out portions to indicate the relationship of the portions which are joined together.

After the dart, indicated by the reference numerals 30 and 31, has been formed in the manner indicated, the blank is cut diagonally beginning at the point 33 along the selvage of the material, thereby forming diagonal edge portions 35 and 36 as shown in Fig. 6. The adjoining edges on the side of the blank are now stitched together to form the rear vertical seam 38 of the garment. It will be appreciated that by varying the grain in the material above and below the stitch line 30 and in the portions of the garment adjacent to the edges 35 and 36, the material may be cut on the bias as shown. Thus when such edges are stitched together, a rear bias seam is formed.

In order to provide additional fullness in the lower or skirt portion of the garment, a triangular godet 40, desirably made from two pieces of material 41 and 42 is stitched to the selvage 43 of the blank. It is desirable when securing two of such edges together that the edges be on the bias of the material in order to provide a far higher order of strength in the seams than would be the case if the edge of the material were parallel with the grain of the material. In the lower portion of the skirt there is no particular tension on the seams and accordingly said bias edges are not normally necessary. In the waist or upper portion of the garment, however, there is considerable strain and the garment in this portion is joined together on the bias edge of the material.

The lower edge of the garment is slightly curved as indicated at 45 and the upper edge of the blank is desirably cut along the lines 46 to pro-

vide a V shaped neck portion 41. The garment is then finished by providing shoulder straps 48.

The preferred embodiment of the invention is provided with only a single vertical seam in the rear of the garment, the lower rear portion, however, having a triangular insert or golet to give fullness in the skirt portion. Material of standard width permits this construction in the moderate sizes and in the event that larger sizes are made, a panel 58, as shown in Fig. 7, extending the full length of the garment, may be secured along its vertical edges 51 to the opposed vertical edges of the main blank. The edges of the main blank along this stitch line are largely on the bias. The dart 30' is formed in the manner previously described. Whereas only one dart is shown in each side of the garment, it will be appreciated that two or more spaced darts may be provided on each side. The essential thing in this regard is to form darts of this character which permits draping the garment to the form of the body by following the various curves thereof and changing the grain of the material from straight in the center front to a progressively increasing bias as it approaches the rear of the garment. This eliminates the necessity for a side seam which normally receives a considerable strain, and permits the placing of the seam in the rear where the strain is considerably reduced. This elimination of the side seams also makes for a smoother fitting hip portion.

What I claim is:

1. A body garment comprising waist and skirt portions and being made from a blank of material, the vertical edges of which are joined together to form a rear vertical seam, the front central portion of the garment being substantially on the straight of the material, each side of the garment being provided with an elongated dart extending from the bust portions through the underarm sections to the rear of the garment, a second dart on each side of the garment extending from the inner end of the elongated dart upwardly over the bust portion, the material above the elongated dart being in a biased position relative to the material below the dart.

2. A body garment comprising waist and skirt portions and being made from a blank of material, the vertical edges of which are joined together to form a rear vertical seam, the front central portion of the garment being substantially on the straight of the material, each side of the garment being provided with an elongated dart extending from the bust portions through the underarm sections to the rear of the garment, a second dart on each side of the garment extending from the inner end of the elongated dart

upwardly over the bust portion, the two edges of the blank which are joined together to form the second dart lying at an acute angle to each other.

3. A body garment comprising waist and skirt portions and being made from a blank of material, the vertical edges of which are joined together to form a rear vertical seam, the front median line of the garment being substantially on the straight of the material, each side of the garment being provided with an elongated dart 10 extending from the bust portions through the underarm sections to the rear of the garment, each dart having a portion extending upwardly and diagonally over the bust portion, the material above the elongated dart being in a biased position 15 relative to the material below the dart, the vertical edges which are joined to form the rear seam being on a bias relative to the front median line of the garment.

4. A body garment comprising waist and skirt 20 portions and being made from a blank of material, the front median line of the garment being substantially on the straight of the material and occupying the central vertical line of the blank, each side of the garment being provided with an 25 elongated dart extending from the bust portion through the underarm section rear of the garment and a short dart at an angle to the elongated dart extending over each bust portion, each bust portion having a cut-out area, two edges of 30 which are joined together to form the short dart, the blank having another cut-out portion extending from the cut-out area to the rear of the garment, the lower edge of such portion extending further towards the front of the garment than 35 the upper edge thereof, such edges being joined together end for end to form the elongated dart.

5. A body garment comprising waist and skirt 40 portions and being made from a blank of material, the front median line of the garment being substantially on the straight of the material and occupying the central vertical line of the blank, a portion extending laterally from each bust portion of the garment, the lower edges of such extension terminating at its inner end in a cut-out 45 area having two edges at an angle to each other, the two edges being joined together to form a short dart and the lower edge of the extension being joined to the adjacent free edges of the blank in biased relation thereto to form an elongated dart 50 extending through the underarm section to the rear of the garment, the opposed vertical edges of the blank being formed along bias lines and being joined to form a rear vertical seam.

HARRIET S. KOHLER.
